Specification of Letters Patent.

Patented Oct. 12, 1915.

Application filed July 9, 1913. Serial No. 778,089.

To all whom it may concern:

Be it known that I, OTTO STRUNK, residing at Friemersheim, Germany, a subject of the Emperor of Germany, have invented a 5 certain new and useful Improvement in Conveyers, of which the following is a specification.

This invention relates to that class of conveying mechanisms which are more particularly intended for the conveyance of coils of wire, and which consist of stationary bars and movable bars which latter are adapted to oscillate vertically as well as in the direction in which the material is to be conveyed, 10 and the object of the invention is to so construct such conveying mechanisms that the direction of travel of the material to be conveyed can be changed at one or more points through an angle of 90°. 15 In the drawing is shown diagrammatically as a constructional example of the subject matter of the invention, a wire conveyer, which consists of a section comprising a hot bed and two other sections which abut on 20 each other and are arranged at right angles to one another, and of which one section serves to convey the coils of wire to the hot bed, and the other section distributes the coils of wire at right angles to the direction 25 in which the hot bed conveys the said coils and over the entire breadth thereof.

In the said drawing Figure 1 is a plan view of the wire conveyer from which certain parts are supposed to be removed, Fig. 35 2 shows in side elevation a portion of the wire conveyer, Fig. 3 is a section on the line 3—3 of Fig. 1 looking from the right. Fig. 4 is a plan view of a portion of the wire conveyer with certain parts in another position. 40 Fig. 5 shows on a larger scale a side elevation of a portion of the wire conveyer, and Fig. 6 is a section on the line 6—6 of Fig. 5 looking from the left with certain parts in another position.

45 Λ , Λ^1 and Λ^2 denote the last three preliminary rollers and Λ^3 the finishing roller of a wire rolling mill. In the vicinity of the finishing roller Λ^3 are four reel standards, mounted in such a manner that the axes of 50 rotation of the four corresponding reels B^1 , B^2 , B^3 , B^4 are situated in the vertical plane determined by the direction of exit of the wire from the finishing roller, and are equidistant from each other. The reel standards

B are constructed in the form of brackets 55 (see Fig. 6), and are each provided, in addition to the bevel gearing b^5 for rotating the axially immovably mounted reel spindles b^6 , with hydraulic mechanism b^7 b^8 for moving the reel hooks b^9 in and out. The construction of the reel hooks b^9 and also of their controlling mechanism are of the well known kind and do not therefore require any further description here.

Beneath the reels B^1 to B^4 is situated the 65 commencement of a conveying section which serves for the reception of the coils of wire C, released by the reel hooks, and for their conveyance on to the hot bed M N. This conveying section has a stationary grate 70 formed of bars D and a movable conveying grate consisting of bars E of equal length. The bars D are supported their lower parts by equidistant teeth d^2 of combs D¹ (see Fig. 6), which are mounted by means of 75 carrier bars d^3 on stationary supports D⁴, arranged in pairs. The movable bars E are arranged between the stationary bars D, are supported in like manner by teeth e^2 of combs E¹. These combs E¹ are rigidly connected by means of two cross bars e^3 to two lateral longitudinal bearers E⁴, which are 80 movable, in the direction in which the material is to be conveyed upon rollers F. Below the bars D are mounted bearing supports F³, in the bearing f^4 of each of which a crank shaft F¹ rotates. Each crank shaft F¹ has two similar and similarly pitched end cranks f^2 , about the crank pins of which the rollers F rotate. The height of the crank 90 shaft F¹ is so arranged that, when the outer cranks f^2 are horizontal, the upper edges of the bars E are on the same level with the upper edges of the bars D. All the crank shafts F¹ carry at their centers a crank f^5 95 pitched in the same direction as the cranks f^2 but at an angle of 90° relatively thereto. The cranks f^5 are connected by their crank pins to a common coupling rod G. The crank f^5 farthest from the rolling mill is 100 connected by a connecting rod G¹ to the shorter crank arm h^1 a shaft H provided with two crank arms h^1 and h^2 and which shaft is driven through spur wheels h^3 , h^4 , h^5 from a driving motor H⁶ (see Fig. 2). 105 The longer crank arm h^2 of the shaft H is set at an angle of 90° relatively to the shorter arm h^1 and is pivotally connected by

a connecting rod J to a rock lever J¹. The free end of the rock lever J¹ is connected by a connecting rod J² to a transverse girder e⁵, which connects the ends of the two longitudinal bearers E⁴ remote from the rolling mill.

The length of the conveying section D E is such that it is capable of receiving a multiple of four coils of wire C. The arrangement is also so constructed that, when the rock lever J¹ is in the left hand extreme position shown in Fig. 2, the bars E are at the same height as the stationary bars D and lie flush and parallel therewith. When on the other hand the rock lever J¹ assumes its right hand extreme position, (indicated by dot and dash lines in Fig. 2) the bars E, which in this position are again at the same height as the bars D, will have been moved relatively to these latter in the direction in which the material is to be conveyed and a distance equal to the distance apart of two adjacent reel axes (see Fig. 4). The radius of the cranks f² is less than the half of the distance apart of two adjacent reel axes, so that the movement of the bars E in a vertical direction is less than it is in the direction in which the material is conveyed. The position which the bars E assume when the rock lever J¹ is in the left hand extreme position will hereinafter be termed the position of rest.

At the end of the conveying section D E there abuts at right angles thereto a second conveying section, the function of which is to distribute the coils of wire over the entire breadth of the hot bed M N and will therefore hereinafter be termed the distributor. The distributor is driven by a shaft K⁶, which extends in the same direction as that in which the material is conveyed by the distributor, and is so positively connected by bevel wheel gearing k⁷ with a number of crank shafts k⁸ carried in bearings K⁴ and each carrying a crank arm k⁹, that all the crank arms are always parallel with each other. To each of the crank arms k⁹, (which are all of equal length) of each two adjacent crank shafts k⁸ is pivotally connected a carrier K so that the parts K k² k³ will have parallel motion. On each of the carriers K is freely mounted after the manner of teeth of combs a group of conveyer bars k¹. All the bars k¹ lie parallel with the bars D and E and therefore at right angles to the direction in which the distributor conveys the material, and all the bars k¹ remain during the rotation of the crank shafts k⁸, in one and the same horizontal plane and, when they are in their central position, are at the same height as the plane of the stationary bars D.

The driving shaft K⁶ is so positively connected by spur wheel gearing k⁷ k³ to the shaft H, that the carrier K next the convey-

ing section D E and projecting into the path thereof when the movable bars are in their position of rest, automatically moves out of the path thereof in the direction in which the distributor conveys the material when the said bars are rocked toward the right. When the bars E are in their position of rest, those of the bars k¹ which in this position are situated in front of the right hand end (see Fig. 1) of the conveying section D E lie exactly in line with and form an extension of the bars E.

Next to the distributor K k¹ at right angles to the direction in which it conveys the material, and on the side remote from the carriers K, is situated the hot bed. This latter has a stationary grate formed of bars M and a movable conveyer grate consisting of bars N of equal length. The mounting of the two grates and the driving mechanism of the movable conveyer grate N which is completely independent of the driving mechanism of the conveyer section D E and the distributor K k¹, is as is clearly shown in Figs. 1 and 2, constructed in the same manner as in the case of the conveyer section D E and need not therefore be further described. The bars M and N are mounted near the distributor K k¹. The free ends m¹ of the stationary bars M extend to near the carrier K. The same is true of the movable bars N, when they are in their left hand extreme position (see Fig. 1). The distances between the bars M and N are exactly equal to the distances between the bars D and E. The bars M and N, lying in front of the right hand end of the conveyer section D E, are so located with relation to the bars D and E that the bars E, when they are rocked toward the right, can pass unimpeded between the free ends of the bars M and N. During the rocking movement imparted to them by the cranks k², the bars k¹ can also pass unimpeded between the free ends of the bars M and N.

The action of the whole apparatus is as follows:—When the front end of a freshly drawn wire emerges, after passing through the preliminary rollers A, A¹ and A², from the finishing roller A³ it is led to the first reel B¹ and wound thereon in the well known manner into a coil C. When the reel B¹ has been wound the wire is cut off and carried on to the second reel B². In this way each succeeding reel is gradually wound. As soon as the coil of wire on the first reel B¹ has been completely wound, the hydraulic controlling mechanism b⁷ b⁸ of this reel is set in motion, whereby the hooks b⁹, which support the coil of wire, are drawn back so that the coil of wire falls on to the part of the conveyer section D E lying beneath the reel B¹ and the movable bars E of which are in the position of rest (see Fig. 1). The reel B¹ is then immediately

got ready for the reception of a fresh coil. The same thing takes place in succession in the case of the succeeding reels. After the last reel B^4 has been wound the wire from the roller A^3 is again led to the reel B^1 , which has in the meantime again become free, and the above described operation is repeated. As soon as the last reel B^4 has let the coil of wire, wound upon it, drop on to the conveyer section $D E$, the driving motor H^6 is set in motion and rotates the shaft H in the direction of the arrow x (Fig. 2) by means of the spur gear h^6, h^4, h^3 . During the first half revolution of the shaft H the rock lever J^1 , as can be followed in detail in Fig. 2, is brought into its right hand extreme position, so that the movable bars E are moved, in the direction in which the material is to be conveyed, into the position shown in Fig. 4, and are simultaneously raised by the rollers F , on the cranks f^2 so that the coils of wire C are carried along with them. Since the movement of the bars E in a vertical direction, is less than it is in the direction in which the material is conveyed, all points of the bars E describe elliptical curves. The advantage of this in comparison with already known arrangements, in which all points of the movable conveyer bars describe circular lines, is that owing to the reduced lift the amount of work required of the driving mechanism is rendered smaller. On the second half revolution of the shaft H , the bars E are rocked under the stationary bars D back into their original position. The coils of wire C remain at this time lying upon the stationary bars D , so that after a complete revolution of the shaft H has taken place they will have been moved on toward the right a distance equal to the distance apart of two reel axes. After four revolutions of the shaft H the driving motor H^6 is again stopped. The four coils of wire C , which originally lay beneath the reels B^1 to B^4 , are now conveyed toward the right a distance equal to the distance apart of four reel axes, so that that portion of the conveyer section which lies beneath the reels, is again free to receive fresh coils. When the four reels B^1 to B^4 have been wound for the second time, and the newly wound coils of wire let fall upon the conveyer section $D E$, there will now be upon this latter $2 \times 4 = 8$ coils situated at equal distances from each other. The driving motor is now again set in motion and only stopped when after four revolutions of the shaft H the eight coils of wire have been conveyed four steps farther onward. The above described operation is repeated in the same manner until the whole conveyer section $D E$ is covered with a multiple of four coils. If now the motor H^6 be again set in motion all the coils on the conveyer section $D E$ will again be moved on one step toward the right during the first revolution of the shaft H . During this time the coil next the distributer $K k^1$ will be deposited by the bars E upon the ends m^1 of the bars M forming the stationary conveyer grate of the distributer and on the ends of the bars N (which are at rest) of the hot bed and which are parallel with the bars M . This can take place unimpeded because the carrier K of the distributer, which is next to the conveyer section $D E$, automatically moves out of the way of the bars E when the bars E are rocked outward as already stated above. During the second revolution of the shaft H the coils of wire on the conveyer section $D E$ will be again moved one step toward the right, so that a second coil will be transferred to the commencement of the distributer. At the same time the coil first transferred to the distributer will be moved farther along thereon by the movable bars k^1 thereof, which during this time have been first raised by the cranks k^2 and simultaneously moved in the direction in which the distributer conveys the material, and then returned to their original position beneath the free ends of the bars M and N . This operation is repeated until after four revolutions of the shaft H the driving motor is again stopped. The conveyer section $D E$ is then completely covered with coils up to the portion lying beneath the reels B^1 to B^4 , and the first four coils are situated on the distributer as is indicated by dot and dash lines in Figs. 1 and 2.

The above described operations are repeated until the distributer, which is capable of holding a multiple of four coils, is completely covered with coils. After this, while the distributer and the conveyer section $D E$ are at rest and a fresh coil is being wound upon the reel B^1 , the driving motor for the movable conveyer bars N of the hot bed is set in motion and is again stopped after the crank shaft of the hot bed driving mechanism corresponding to the shaft H has made one complete revolution. During this movement all the coils of wire on the distributer are lifted by the free ends of the bars N , conveyed toward the right and deposited upon the hot bed, so that the distributer again becomes at liberty to receive a fresh series of coils of wire. The driving mechanism of the hot bed N remains at rest until the distributer is again entirely covered with coils of wire. It is then again set in motion and conveys the series of coils of wire already on the hot bed one step farther toward the right. The series of coils of wire on the distributer will be simultaneously transferred in the manner described to the hot bed, so that the distributer is again capable of receiving a fresh series of coils of wire. The cycle is repeated until the hot bed is completely covered. When

they have reached the end of the hot bed the coils of wire are cooled and removed by hand to be bundled and shipped.

In the above described arrangement, the 5 driving shaft K^6 of the distributer is permanently in positive connection through the gear wheels k^7 and k^8 with the shaft H , so that when the bars E are moved the bars k^1 of the distributer are also moved with them 10 even when the distributer is not covered.

I claim:

1. A conveyer mechanism comprising a series of stationary bars and a series of 15 movable bars parallelly positioned in a plurality of groups, the movable bars of one group adapted to move in a transverse direction relative to the direction of movement of the bars of the other group.

2. A conveyer mechanism comprising a 20 series of stationary bars and a series of movable bars parallelly positioned in a plurality of groups, the movable bars of one group adapted to move in a transverse direction relative to the direction of movement of the bars of the other group; the 25 ends of the movable bars of the first group, when in their forward position, adapted to engage between the ends of the stationary bars of the other group.

3. A conveyer mechanism comprising a 30 series of stationary bars and a series of movable bars parallelly positioned in a plurality of groups, the movable bars of one group adapted to move in a transverse direction relative to the direction of movement of the bars of the other group, the 35 ends of the movable bars of the several groups adapted alternately to engage between the ends of the stationary bars of one 40 of the groups.

4. A conveyer mechanism comprising a series of stationary bars and a series of 45 movable bars parallelly positioned in a plurality of groups, the movable bars of one group adapted to move in their longitudinal direction and the movable bars of another group adapted to move in their transverse direction.

5. A conveyer mechanism comprising a 50 series of stationary bars and a series of movable bars parallelly positioned in a plurality of groups, the movable bars of one group adapted to move in their longitudinal direction and the movable bars of another 55 group adapted to move in their transverse direction, and means for moving the bars of the second group both in the transverse and the vertical direction.

6. A conveyer mechanism comprising a 60 series of stationary bars and a series of movable bars parallelly positioned in a plurality of groups; one of said groups constituting a hot bed having its bars arranged in the direction in which the material is to be 65 conveyed, and means for simultaneously

moving all the movable bars in said group; all the bars of the second group being mounted on a carrier, and means for driving said carrier, independent of said first moving means, to oscillate its bars in a 70 direction transverse to the longitudinal direction of the bars; said carrier with its bars being situated at the receiving side of the hot bed; whereby the bars of the second group during their oscillation may pass 75 freely between the ends of the bars of said hot bed.

7. A conveyer mechanism comprising a series of stationary bars and a series of 80 movable bars parallelly positioned in a plurality of groups; one of said groups constituting a hot bed having its bars arranged in the direction in which the material is to be conveyed, and means for simultaneously moving all the movable bars in said group; 85 all the bars of the second group being mounted on a carrier, and means for driving said carrier, independent of said first moving means, to oscillate its bars in a direction transverse to the longitudinal 90 direction of the bars; said carrier with its bars being situated at the receiving side of the hot bed; whereby the bars of the second group during their oscillation may pass 95 freely between the ends of the bars of said hot bed; the third group mounted and moved in a similar manner to said first group and constructed to deliver to said second group; the movable bars of the three groups being constructed to be oscillated by 100 said second driving means in such a manner that said carrier with its bars directly moves out of the way of the movable bars of the third group when said last mentioned bars are moved in the direction toward the bars 105 of the second group.

8. A conveyer mechanism comprising a series of stationary bars and a series of 110 movable bars parallelly positioned in a plurality of groups, the movable bars of one group adapted to move in their longitudinal direction and the movable bars of another group adapted to move in their transverse direction; said movable bars of the first group having a greater movement in their 115 longitudinal direction than in their vertical direction; the material being conveyed in the longitudinal direction of said bars of the first group.

9. A conveyer mechanism comprising a series of stationary bars and a series of 120 movable bars parallelly positioned in a plurality of groups, the movable bars of one group adapted to move in their longitudinal direction and the movable bars of another group adapted to move in their transverse direction, and means for simultaneously moving said movable bars of both groups, said means comprising rocking levers and members connected with said transversely 125 130

moving bars, and rollers on said levers supporting said longitudinally movable bars, whereby the rocking movement given to said rollers will be imparted to said bars in the direction in which the material is conveyed, the lift of said bars being greater than the lift of the rollers during their rocking movement in a vertical direction.

The foregoing specification signed at Barmen, Germany, this 21st day of June, 1913.
